UNITED STATES PATENT OFFICE.

WILFORD G. BARTENFELD, OF LORAIN, OHIO.

CHANNEL AND PLATE CONSTRUCTION FOR VESSELS.

Application filed May 19, 1926. Serial No. 110,125.

This invention relates to the construction for the hulls of steel vessels, and more particularly to the use of channels and plates in the construction of the hulls of vessels having the usual shaped pointed bow and rounded stern.

There are important advantages in constructing the hulls of vessels of channels, such for instance as no rivets passing through the shell and the flanges of the channels strengthen the shell against indentation and also prevent buckling of the vessel. While it is desirable to construct vessel hulls of channels, it is difficult and expensive to make channels conform to the shape necessary in forming the bow or stern and therefore not practical. In order to gain the advantages of channel construction and yet shape the bow and stern as desired at reasonable cost, this invention contemplates the use of both channels and plates.

For a clear understanding of the invention, reference will be had to the accompanying drawings illustrating the same, and the novel features thereof will be distinctly pointed out in the appended claims.

In the several views of the drawings, similar characters of reference indicate corresponding parts.

Figure 1 is a side elevation of the hull of a steel vessel constructed in accordance with my invention.

Fig. 2 is a plan view taken on line 2—2 of Fig. 1, illustrating the construction at the upper portion of the hull,

Fig. 3 is a side elevation of a modification, channels being substituted for the plates forming the bulwarks,

Fig. 4 is a plan view of Fig. 3,

Fig. 5 is a fragmental cross sectional view taken on line 5—5 of Fig. 1, and

Fig. 6 is a cross sectional view taken on line 6—6 of Fig. 3.

Referring to the drawings 1 represents a plurality of channels of standard construction, which are connected together at their flanges by rivets or bolts or in any other suitable manner as indicated at 2. The channels are connected together at their adjoining ends by butt straps 3 or in any other suitable manner, and the channel construction gradually increases in length from the bottom 4 towards the top of the hull. The forward portion of the upper channels are curved inwardly as shown at 5. Plates 6 overlap the outer sides of the upper channel

7, and the forward plates thereof, as indicated by 8, are curved inwardly to form the bow, while the rear plates 9 are curved to form the stern of the hull of the vessel. 60

Plates of suitable width and length, as indicated by 10, overlap the forward ends of the channels 1 at 11 and the upper one of these plates the lower longitudinal portion of the plate 8, and these plates are 65 curved to form the desired shape of the bow, and plates 12 overlap the rear ends of the channels 1 at 13 and the upper ones of these plates the lower longitudinal portions of the plates 9, and these plates are suitably curved 70 to form the stern of the hull of the vessel.

The deck of the vessel, indicated by 14, is constructed of plates or channels, the side edges of which are supported by angle bars 15, which are connected to the side plates 75 6, 8 and 9. Said deck is located at a suitable distance below the upper edge of the plates 6, 8 and 9, so that the upper portions of said plates provide a gunwhale or enclosure for the deck. Plates indicated by 16 80 and 17, are connected to the plates 6, 8 and 9 and form the bulwarks at the forward and rear ends of the vessel.

The joints between the various plates may be constructed by overlapping as at 11 and 85 13 or by means of butt straps as at 18 according to location and desire.

Instead of employing the plates 16 and 17 to form the bulwarks, channels indicated by 19 may be employed for forming the bow 90 of the vessel and channels 20 for the stern. These channels are cut off on a curve as indicated at 21 and 22 respectively and are curved inwardly to proper form for the bow and stern, and their adjoining ends are connected together by butt straps as at 23 or in any suitable manner. The deck is formed of channels 24 or plates, which are connected to the upper channel 7 by means of an angle bar 25. 95

From the drawings and description, it will be seen that the hull of a steel vessel having the usual shaped bow and stern may be constructed of channels and plates of standard construction in a practical manner 105 and within prohibitive cost. It will be understood that various changes in the details of construction may be made and still keep within the scope of the claims.

Having fully described my invention, 110 what I claim is:

1. In a hull for vessels, the combination

of channels, forming the sides of the hull intermediate the ends thereof, and plates connected to said channels forming the ends of the hull.

5. 2. In a hull for vessels, the combination of channels, the channels being connected together at their flanges for forming the sides of the hull intermediate the ends thereof, plates connected to the ends of said channels, and said plates being curved to form the bow and stern of the hull.

3. In a hull for vessels, the combination of channels, the channels being connected together at their flanges for forming the 15 sides of the hull intermediate the ends thereof, plates connected to the ends of said

channels, forming the bow and stern, and plates connected to the upper channel and the upper plates of said plates forming the bow and stern.

4. In a hull for vessels, the combination of channels forming the sides of the hull intermediate the ends thereof, plates connected to the ends of said channels forming the bow and stern, plates connected to the upper channel and the upper plates of said plates forming the bow and stern, and a deck supported by the last mentioned plates

20 25
In testimony whereof I affix my signature.

WILFORD G. BARTENFELD
